BLOWTORCH

Filed Aug. 5, 1926

UNITED STATES PATENT OFFICE.

BRUNO MARTIN, OF SAGINAW, MICHIGAN.

BLOWTORCH.

Application filed August 5, 1926. Serial No. 127,265.

This invention relates to certain new and useful improvements in blow torches or forges, and it has for its objects among others to provide an improved torch which shall produce the highest degree of heat, require less pumping, having provision for the maximum amount of air pressure, together with provision for preventing the dripping of the gasoline and its overflow onto the floor or over the side of the tank, thus obviating the danger of fire, protecting life and property, and at the same time the oil from the drip cup will aid to generate the burner.

I provide a corrugated burner tube which serves to produce the greatest amount of heat, and I provide novel means for supporting the pump, utilizing the lateral support for the flow of air to the top of the tank, and disposing the air tube exteriorly of the tank and extending the same upward to the top of the tank.

I further provide means for holding the valve stem and piston down after the air has been pumped into the top of the tank.

Other objects and advantages of the invention will hereinafter appear, and the novel features thereof will be specifically pointed out in the appended claims.

The invention, in its preferred form is clearly illustrated in the accompanying drawings, which, with the numerals of reference marked thereon, form a part of this specification, and in which

Figure 1 is a side elevation, with parts broken away and others in section, to better show the construction and arrangement of some of the parts.

Figure 2 is a view at right angles to Figure 1.

Like numerals of reference indicate like parts in the different views.

Referring to the drawings

1 designates the tank, which is of tapered form as shown in order to provide the greatest amount of air pressure in a manner which will be readily understood, which, in turn, reduces the amount of pumping required.

2 is the top of the tank. Its upper surface is concaved as seen at 3 to form a receptacle for the gasoline and to prevent the dripping of the latter and overflowing onto the side of the tank and floor, and in this way it eliminates the danger of fire as will be readily understood.

Secured in and rising from the top 2 is a pipe 4 threaded into the top, or otherwise affixed therein, the upper end of the said pipe being screw threaded as seen at 5 and having a collar 6 thereon, and between this collar and a collar 7 on the pipe near its junction with the top is a drip cup 8, held in proper position by any suitable means, as the screw 9. This drip cup may be of any well known or approved form, suited to the purpose.

10 is the wick, of any suitable character, extending down within the tank and its upper end extended through the screw threaded upper end of the pipe 4 and entering the nipple 11 depending from the casting 12, the latter being screw threaded to engage the threaded upper end of the pipe 4. The member 11 has threaded therein the member 13 which is provided with the minute opening 14 controlled by the needle valve or point 15 the latter being regulated by the handle 16 on the valve stem 17 as seen in Figure 1.

The member 13 extends beyond the end of the casting 12 as shown and receives the internally threaded end of the burner tube 18, which latter is fluted or corrugated upon its exterior as seen at 19 its outer end being open as usual and the tube being provided with a multiplicity of lateral openings 20, as seen in Figure 1, the perforations extended from between the walls of the corrugations.

In assembling these parts, the pipe is affixed in position in the top of the tank, the drip cup is placed in position and secured where desired by its screw, the wick having been previously placed in position, or this may be done after the pipe is placed in position and then the casting and the burner tube are placed in position.

On the burner tube is a soldering iron support 21.

It is to be noted that the member 13 may be integral with the casting 12, or a separate piece carried thereby.

22 is a lateral member from the tank near its upper end, and on this and communicating therewith is a filling cup 23, provided with a cap 24, 25 being a valve fitted to a seat 26 at the bottom of said cup, as seen in Figure 1, the valve being carried by a stem 27 provided with a suitable handle 28, as seen in Figures 1 and 2. This member 22 has a passage 29 communicating with the

interior of the tank near the top of the latter as seen in Figure 1.

The lateral member 22 is extended to form a support for the upper end of the pump cylinder 30, which is provided with a rubber or analogous cover 31, shown clearly in Figure 1.

The lower end of the pump cylinder is supported by the lower lateral tubular member 32 which communicates with the cylinder of the pump as seen in Figure 1 and with the vertical pipe 33 which latter is disposed outside of and along the wall of the tank as seen in Figure 1.

Within the pump cylinder is a piston 34 carried by the stem 35, provided with a suitable handle 36 by which it may be reciprocated, for the purpose of pumping air to the top of the tank.

In order to hold the valve stem down I provide the latter with a lateral member 37 with which is designed to engage a pivoted member, or the equivalent, 38, hinged as at 39, to the member 40 secured to the lateral member 22, as shown clearly in Figure 1.

In use, the tapered tank provides for a maximum amount of air pressure and less pumping is required, while the corrugated burner tube and drip cup produce the greatest amount of heat. By reason of the taper of the tank the device as a whole rests most securely upon any support and is not liable to be tipped over. The disposition of the supply tube 33 outside the tank instead of within the same economizes construction, saves in cost and strengthens the tank.

The torch may be made of copper, aluminum, or any other material suited to the purpose.

The pipe 33 may be caused to communicate with the passage 29 in the lateral member 22 and through it into the tank, or communicate directly with the interior of the tank through an opening in the wall of the latter.

The construction and mode of use is so apparent that a detailed description of the latter is not deemed necessary.

Modifications in detail may be resorted to without departing from the spirit of the invention or sacrificing any of its advantages.

As seen in Figure 1 the minute opening 14 may be formed in a separate member 41 made in the form of a threaded plug which

screws into the chamber; this is desirable as it provides for ready removal for cleaning purposes, and also serves to increase the gas pressure and thus give increase in power.

The front end of the burner tube is reduced in diameter with the outer portion cone shaped as seen at 42 in Figure 1; by this means the stream of flame coming out of the smaller hole will be more concentrated and form a greater melting flame.

What is claimed as new is:—

1. In a blow torch, a tapered tank, lateral hollow supports thereon, an air pump on and in communication with said supports, and a pipe lying against and secured to the outer wall of the said tank and closely contacting therewith and communicating with one of the said lateral supports and with the tank.

2. In a blow torch, a tank, an air pump supported thereby and entirely exterior thereof and communicating therewith, a pipe connecting said hollow lateral members and connecting them with said tank, said pipe secured in close contact with the wall of the tank, and communicating with one of the hollow members, and interengaging means on the stem of the pump piston and the support of the pump for holding the piston in its lowered position.

3. In a blow torch, a tank, a pump, a hollow lateral member connected with the latter at the lower end, a lateral member at the upper end of the pump, and a tubular member rigid with the tank and closely contacting therewith, said supporting member being in communication with the pump, said tubular member being also rigid with the lateral members and in communication with the tank.

4. In a blow torch, a tank, a pump, a lateral hollow member connected with the latter at the lower end, a lateral member at the upper end of the pump, a tubular member rigid with said lateral members and in communication with the pump, said tubular member closely contacting with the outer wall of the tank, said tubular member being also in communication with the tank, and a filling cup mounted on the upper lateral member and emptying laterally into the tank.

In testimony whereof I affix my signature.

BRUNO MARTIN.
